AIRCRAFT FLOAT LIGHT OR SMOKE BOMB

Harry J. Nichols, Dayton, Ohio

Application October 22, 1932, Serial No. 639,125

16 Claims. (Cl. 102—24)

(Granted under the act of March 3, 1883, as
amended April 30, 1928; 370 O. G. 757)

My present invention relates to improvements in aircraft float lights or smoke bombs which are adapted to be dropped from air craft for any of the various purposes for which such devices may be or are usually employed.

The objects of the present invention are to provide a light or bomb of simple and inexpensive construction that will withstand dropping from high altitudes without impairment, which will float on the surface of water, and which after being dropped may be relied upon to produce for a substantial interval an illumination or signal light, a smoke screen or a toxic vapor or gas according to the ingredients contained therein, independent of the surface conditions of the water.

Other objects will be apparent from the following description and accompanying drawing.

In the drawing, Fig. 1 is a longitudinal, axial, 20 sectional view of a device embodying my invention;

Fig. 2 is an enlarged similar view of the upper portion of Fig. 1;

Fig. 3 is an enlarged central, axial, sectional 25 view of the starter cup and its contents.

In the drawing, in which like characters of reference indicate the same parts, 10 denotes the body portion of the float light or bomb which is preferably made of light wood of a size to obtain the desired buoyancy and having a longitudinal bore comprising portions 11 and 11a of different diameters, extending completely therethrough, 11a being the larger.

The upper or rear end of body 10 is provided 35 with a shallow recess 13 forming a shoulder 14 at the outer end of opening 11. A cup 15 is disposed in recess 13 with its edge upon shoulder 14. Cup 15 has one or more openings 16 in the base thereof, which opening or openings are adapted 40 to be covered by a member 17 formed of adhesive tape or other material adapted to be released in part or in whole by pressure within the bore 11. The cup 15 is secured in position by a sealing medium 18, which may be paraffin or like material, poured into recess 13 and congealed therein in contact with the wall of recess 13 and the exterior surface of the cup 15, as shown in Fig. 2.

A starter cup 20 has an opening in its bottom 50 through which is forced a larger diameter tube 21, which flares the edge of the opening outwardly. The flared edge of the opening in the cup 55 grips the tube 21 and maintains the same in position with the tube extending substantially below as well as above the bottom of cup 20. Within tube 21 is a doubled quick match fuse 22 whose

looped upper end projects above the tube 21 into the cup 20, which cup is filled with a slow burning powder that generates but little gas while combusting. The top of cup 20 is provided with a cover 23 fitted into its top and provided with one or more openings 24 therethrough which are covered by a member 25 preferably formed of a disk of adhesive tape or other suitable material that adheres to the top of cover 23.

The outer diameter of cup 20 substantially 10 conforms to the diameter of opening 11a in body 10 and cup 20 is adapted to be inserted into the lower end of opening 11a in body 10 with its upper portion resting against the shoulder 12 in body 10 with element 25 lying within opening 11.

One or more pellets 30 of slow burning illuminating material, dense smoke producing material or toxic vapor producing material, as may be desired, of substantially the diameter of opening 11a and having central vertical opening 31 extending therethrough are adapted to be inserted into opening 11a with opening 31 in the upper pellet 30 receiving the tube 21 and its extended quick match fuse 22 that has a burning 25 time sufficient to permit the bomb to become stabilized on the water before igniting the charge of the bomb. The lower or forward end of opening 11a is closed by a wood disk 33 having vertical opening 34 therethrough in substantial alignment with tube 21 and openings 31. Wood disk 33 may be secured in place by one or more nails 35 driven through the adjacent portion of body 10 and into said disk 33, as shown in Fig. 1.

The lower or forward end of body 10 is rabbeted 35 at 36 adapted to receive the wall 37 of fuse stock 38. Wall 37 is provided with a plurality of openings through which are passed nails or screws 39 extending into the wood body 10 for securing the fuse stock 38 to the forward or lower end of body 40 10, the wall 37 extending over and preventing the dislodgment of the nails or other securing devices 35.

Fuse stock 38 is provided with a central longitudinal opening of two diameters, the smaller 45 diameter being adapted to receive a tube 40 wherein are mounted a fuse 61 including a primer adapted to be detonated by being struck by firing pin 62 when the pin is driven inwardly by water forced by impact through opening 63 against 50 piston 64 that is slideable in member 40. A spring 65 normally holds firing pin 62 away from the primer. A sealing disk 41, adapted to be ruptured by impact of the device upon water, closes opening 63 in plug 42. This firing mechanism forms 55

the subject matter of my copending application for Water-impact fuses, Serial No. 639,126, filed October 22, 1932.

The upper or rear end of body 10 is preferably provided with a tapered surface 43. On this tapered surface 43 are mounted a plurality of fins 44 each having a flange 45 through which securing devices 46 are passed to secure the same to the body 10. The rear end of body 10 is so thin as to render impracticable the securement of the upper or rear end of fins 44 by the means heretofore described for the securement of the lower or forward ends thereof. To obviate this difficulty, I have devised a securement for the rear ends of fins 44 by forming a hole 50 through each fin 44 near its upper inner corner and passing a wire 51 through all of the holes 50 and around the upper or rear end of body 10.

The parts are normally in the position shown in Fig. 1 and remain in such position until the hereafter stated changes occur therein.

When the subject device is launched from the aircraft, it is maintained in a vertical position at least in the latter portion of its flight by the stabilizing fins 44 as well as by the fact that its center of gravity is well toward its forward or downward end in the position shown in Fig. 1. The impact fuse is in no way acted upon during the release or the flight through the air, but only produces the detonation of its fuse pellet upon impact with water when and if the fuse stock 38 is provided with a fuse, as shown. However, any other type of fuse may be provided in the fuse stock 38 which will produce detonation or deflagration at a different time or in a different manner.

Upon detonation of the fuse pellet within the fuse unit, the products of such detonation are passed upwardly through tube 60 and opening 31 where the quick match fuse 22 is ignited which, at its upward or bent end, ignites the starter charge content of cup 20 whose heat pressure may partially release the sealing disks 25 and 17. The burning of the starter charge within the cup 20 melts through the thin zinc cup 20 and ignites the top end of the upper pellet 30, if it be a floating light or smoke bomb, or starts the release of the toxic gas content of 30 if the same be a toxic bomb. The resulting products of the pellets 30 rise through opening 11. The aforesaid combustion melts or consumes the cover 23, which affords a greater pressure and volume of supply of the products of 30 to opening 11, which greater pressure may blow out the cup 15 from the mouth of opening 11, thus permitting free egress of the flame, smoke or toxic material from opening 11.

Where the pellets 30 are formed of pyrotechnic composition, such composition may be such as is disclosed in my Letters Patent No. 1,419,295.

By reason of the buoyancy of the body 10 and its very low center of gravity, the device will float upon the surface of the water and be maintained in a vertical position thereon, to which position it is immediately returned if displaced therefrom.

The temporary closure by the seals 17 and 25 initially keeps water from entering opening 11 from the top and the stock 38 and its joint with the body 10 is water-tight and prevents the entry of water from the lower end of the device.

The initial combustion produces but a relatively slight pressure in opening 11, first by the heating of the air content thereof, which heat beyond a certain degree tends to weaken the grip of the adhesive seals 17 and 25. The pressure in opening 11 is further augmented gradually by the

combustion of the content of cup 20 and then rapidly by the burning of units 30. When the initial pressure on seals 25 and 17 becomes sufficient, the seal 25 is partially released and later the seal 17 is partially released. Prior to and during such partial release there is no opportunity for water to enter through either of such seals, first because of their sealed condition and second, in their partially unsealed condition the escaping gas prevents the ingress of water. When the reaction of the pellets 30 has proceeded for a short time, the sealing members 25 and 17 and disk 15 are blown out and the volume and force of the gases escaping through opening 11 are such as to preclude the entrance of water into the interior of the body 10.

It will be apparent that my invention produces a very simple, inexpensive, efficient and dependable device for the performance of the stated functions under normal as well as abnormal conditions, and which will be unimpaired in the performance of its functions by the shock of impact, or otherwise.

It will be understood that the above description and accompanying drawing comprehend only the general and preferred embodiment of my invention, and that various changes in construction, proportion and arrangement of parts may be made within the scope of the appended claims without sacrificing any of the advantages of this invention.

The herein described invention may be manufactured or used by or for the Government of the United States for governmental purposes without the payment of any royalty thereon.

What I claim is:

1. In a bomb, the combination of a normally water-tight buoyant body having a cavity therein provided with an outlet passing through a portion of said body, said cavity being adapted to contain a charge, a fuse carried by said body and adapted to initiate the reaction of such charge upon impact with water, a member adapted to cover said outlet and provided with an opening therethrough, a cover for said opening releasable by heat, means for removably securing said cover in its covering position, and means susceptible to softening by heat for removably securing said member over said outlet.

2. In a bomb, the combination of a normally water-tight buoyant body having a cavity therein provided with an outlet passing through a portion of said body, said cavity being adapted to contain a charge, a fuse carried by said body and adapted to initiate the reaction of such charge, a member adapted to be inserted into and close the mouth of said outlet, and means releasable by the heat of reaction of said charge for securing said member in said mouth.

3. In a bomb, the combination of a body having a cavity therein provided with an outlet and adapted to contain a charge, a fuse carried by said body and adapted to initiate the reaction of such charge, a member adapted to be inserted into and close the mouth of said outlet and having an opening therethrough, means for securing said member in said mouth releasable by the reaction of said charge, means for covering said opening through said member, and means for securing said cover to said member adapted to release said cover prior to the release of said member.

4. In a bomb, the combination of a body having an opening extending longitudinally therethrough and of larger diameter at its forward end, said larger diameter opening being adapted to con-

- tain a charge provided with an independent communication path therethrough, a fuse at the forward end of said independent path of communication, preliminary combustion means at the opposite end of said path adapted to be ignited by said fuse, an apertured disk between the different diametered portions of said opening through said body adapted to be disintegrated by the combustion means, and removable means for closing said aperture through said disk and adapted to be released prior to the disintegration of said disk.
5. In a bomb, the combination of a body having an opening extending longitudinally therethrough whereof the forward portion is of larger diameter than the rear portion, separate means for closing said opening at an intermediate point and at each end, each of said closure means having an aperture therethrough, and releasable means for normally closing said aperture at the rear end and 10 at said intermediate point.
6. In a bomb, the combination of a body having an opening extending longitudinally therethrough whose forward portion is of larger diameter than the rear portion, a plug having a hole there-through secured in the forward end of said opening, disks each having an aperture therethrough normally closing said opening at its rear end and at the juncture of its different diameters, and releasable means for normally closing said apertures.
- 30 7. In a bomb, a combustion receptacle having a body and a closure formed of material adapted to be disintegrated by the combustion of its content, said body and closure each having an aperture therethrough, a tube of larger diameter than the aperture in said body forced therethrough, and a cover for the aperture of said closure adapted to be released prior to the time said closure may be disintegrated.
- 40 8. In a bomb, the combination of a body portion of wood having an opening therethrough of larger diameter at its forward portion, a disk of wood having a hole therethrough and adapted to be secured in the forward end of said opening, and a nose piece secured to said body and enclosing said disk and its securing.
9. In an illumination, smoke screen or toxic bomb, the combination of a body portion of wood having an opening in its top and its exterior 50 tapering downwardly and outwardly from its top, a plurality of fins each having a flange on its inner edge adapted to contact with said tapering surface, means for securing the lower inner portion of each fin to said body, and a wire extending through the upper inner portion of each fin and around the adjacent body portion.
- 55 10. In a bomb, the combination of a normally water-tight buoyant body having a cavity therein provided with an outlet and adapted to contain a charge, the center of gravity to said body being nearer the end thereof opposite said outlet than to the outlet, a fuse carried by said body and adapted to initiate the reaction of such charge, a member adapted to cover said outlet and provided with an opening therethrough, a cover for said opening, means for removably securing said cover in its covering position and means formed of material different from that of said body for removably securing said member over said outlet, said last mentioned means being susceptible of softening by heat.
- 70 11. In a bomb, the combination of a normally water-tight buoyant body having a cavity
- therein provided with an outlet and adapted to contain a charge, a fuse carried by said body and adapted to initiate the reaction of such charge, a member insertable into said outlet to close the mouth thereof and means other than the material of said body releasable by the reaction of said charge for securing said member in said outlet, said last mentioned means being susceptible of softening by heat.
12. In a buoyant bomb adapted to function upon impact with water, the combination of a body having an axial cavity therein provided with a normally sealed outlet and adapted to contain a combustible charge, a water operated fuse carried by said body and adapted upon impact with water to initiate the ignition of said combustible charge, heat-releasable closing means for said outlet provided with venting means, and pressure-releasable sealing means for said venting means.
- 20 13. A bomb adapted for functioning while submerged or floating in water including a buoyant normally water-tight body having an axial cavity therein provided with a normally closed outlet and adapted to contain a combustible charge, a fuse carried by said body and adapted to initiate the ignition of said combustible charge, impact actuated means to ignite said fuse, and closure means for said outlet adapted to be weakened and partially opened by heat and subsequently entirely removed by pressure to gradually open said outlet to permit egress of gases from said combustible charge without permitting ingress of surrounding water and ultimately leave said outlet wholly unobstructed.
- 30 14. In a bomb of the class described, the combination of a body having an axial cavity therein provided with a normally sealed outlet and adapted to contain a combustible charge, a fuse in said cavity combustible means, and means adapted to be weakened by heat and subsequently entirely removed by pressure to open said outlet partially to permit egress of gases from said starter means and to open said outlet completely to permit egress of gases from said combustible charge.
- 35 15. In a bomb adapted to function in water, the combination of a body having a cavity therein provided with a normally closed outlet and adapted to contain a combustible charge, a fuse carried by said body and adapted to initiate the ignition of said combustible charge, sealed container means for said starter means, sealing means for said container means releasable by heat, and closing means for said outlet adapted to be weakened by heat and subsequently entirely removed by pressure to leave said outlet wholly unobstructed.
- 40 16. In a bomb of the class described adapted for functioning in water, the combination of a buoyant body having an axial passage extending to the rear end thereof, a combustible charge within said passage, a water operated fuse, starter means positioned in said passage in a protective position rearwardly of said charge and in igniting relation thereto, sealing means for said starter means, and sealing means for the rearward outlet of the aforesaid axial passage adapted to be weakened by heat and subsequently entirely removed by pressure to leave said outlet wholly unobstructed.

HARRY J. NICHOLS.
